SWINGING DEVICE FOR BRIDGES OF POWER DRIVEN VEHICLES

Filed Oct. 13, 1924

UNITED STATES PATENT OFFICE.

PAUL GÖTZELMANN, OF STUTTGART, GERMANY, ASSIGNOR TO DAIMLER-MOTOREN-GESELLSCHAFT, OF STUTTGART-UNTERTURKHEIM, GERMANY, A CORPORATION OF GERMANY.

SWINGING DEVICE FOR BRIDGES OF POWER-DRIVEN VEHICLES.

Application filed October 13, 1924. Serial No. 743,459.

To all whom it may concern:

Be it known that I, PAUL GÖTZELMANN, a citizen of the State of Prussia, Germany, residing at Stuttgart, Olgastrasse 81, Germany, have invented certain new and useful Improvements in a Swinging Device for Bridges of Power-Driven Vehicles, of which the following is a specification.

This invention relates to mechanism for 10 the lateral and backward swinging of bridges or bodies of power-driven dump vehicles, in which the lifting mechanism, which is used for the swinging of the bridge or body, is provided within a casing pivotally 15 mounted to swing around an axis positioned in the longitudinal direction of the vehicle and in which the driving shaft is carried through one of the pivots of the casing.

In comparison with known constructions, 20 in which for instance the rack of a hoist constructed in the form of a lifting device is operatively connected to the swinging bridge, the construction according to this invention has the advantage, that the member 25 operating the bridge will be of smaller length and that the time required for the swinging of the bridge or body is rendered shorter.

In the accompanying drawing an example 30 of carrying this invention into effect is shown in which Fig. 1 is a front elevation of the invention, parts of the casing being in section, and Fig. 2 is a side view of the device in discharging position.

The shaft *a*, which is driven by the motor 35 of the vehicle carries on the one of its ends a cog-wheel *b*, which meshes with a further cog-wheel *c* mounted on a jack shaft which also carries a worm *d*. The latter meshes with the worm-gear *e*, which drives the 40 cranks *g* mounted upon the ends of the crank shaft *f*. With the cranks *g* are connected the operating rods *h*, which are connected by means of the clip or yoke *i* with the swinging bridge or body *k*. The bearings *l* and *m* of the casing *n* have a common 45 axis, which is positioned in the longitudinal direction of the vehicle, the casing together with the lifting mechanism swinging around this axis during lateral swinging of the bridge. For this purpose the driving shaft

a is carried through the bearing *l* of the casing.

The device according to this invention has the special advantage of simplicity and by reason of the crank-motion permits a quick 55 raising and lowering of the swinging bridge.

I claim:

1. A device of the character described having in combination, a vehicle dump body, a casing pivotally mounted to swing about an 60 axis parallel to the longitudinal axis of the vehicle, a power operated drive shaft having one end extending through the casing and arranged in axial alignment, with the casing pivots, a crank shaft supported within the casing and arranged transversely of the vehicle frame, means within the casing for actuating the crank shaft from the power driven shaft, crank arms upon the ends of the crank shaft, the said arms being 70 connected to the dump body whereby the latter is swung into dumping position upon rotation of said crank shaft.

2. A device of the character described having in combination, a vehicle dump body, a 75 casing pivotally supported below said body to swing about an axis extending longitudinally of said vehicle, a driven shaft extending through the casing and forming one of the pivots thereof, a crank shaft within the 80 casing, a gear upon the inner end of the driven shaft, a jack shaft rotatably mounted in bearings formed in the front and rear walls of the casing, a gear on the jack shaft adapted to mesh with the gear on the driven 85 shaft, a worm on the jack shaft, a gear on the crank shaft adapted to mesh with the said worm, crank arms upon the ends of the crank shaft, a yoke pivotally connected to the bottom of the dump body, and means 90 connecting the crank arms to the ends of the yoke whereby the dump body is swung into dumping position upon rotation of the crank shaft.

In testimony whereof I affix my signature 95 in presence of two witnesses.

PAUL GÖTZELMANN.

Witnesses:

H. TAYLOR,
JORDAN BAUER.
